UNITED STATES PATENT OFFICE.

ARTHUR M. KING, OF KIDDERMINSTER, ENGLAND, ASSIGNOR TO HENRY JECKS DIXON & SONS, OF SAME PLACE.

DESIGN FOR A CARPET-PATTERN.

Specification forming part of Design No. 6,092, dated August 27, 1872.

To all whom it may concern:

Be it known that I, ARTHUR MAZEPPA KING, of Kidderminster, in the county of Worcester, in England, have invented a new and original Design for Carpets; and I do hereby declare that the following is a full, clear, and exact description thereof, which will enable others skilled in the art to make and use the same, reference being had to the accompanying photographic illustration forming part of this specification.

The design consists of an ellipse containing a smaller ellipse, connected to the first by four

ovoid disks, placed one at each end and side. A wide band runs behind the smaller diameter. Said principal ellipse, at the end, laps a still larger figure of alternate curved and angular outlines surrounding an ornamental center.

I claim as my invention—

The design for carpets, as shown.

ARTHUR MAZEPPA KING.

Witnesses:

JOHN JEROME,

JOHN W. CHADWICK,

Kidderminster.
